UNITED STATES PATENT OFFICE.

FRANK E. LARSCHEID, OF MINNEAPOLIS, AND FREDERICK W. CARLSON, OF ST. PAUL,
MINNESOTA, AND JOSEPH FIRNER, OF PRESCOTT, WISCONSIN.

PIVOT-HINGE.

1,162,936.

Specification of Letters Patent.

Patented Dec. 7, 1915.

Application filed September 28, 1914. Serial No. 863,869.

To all whom it may concern:

Be it known that we, FRANK E. LARSCHEID, citizen of the United States, residing at Minneapolis, in the county of Hennepin and State of Minnesota, FREDERICK W. CARLSON, citizen of the United States, residing at St. Paul, in the county of Ramsey and State of Minnesota, and JOSEPH FIRNER, citizen of the United States, residing at Prescott, in the county of Pierce and State of Wisconsin, have invented certain new and useful Improvements in Pivot-Hinges; and we do hereby declare the following to be a full, clear, and exact description of the invention, such as will enable others skilled in the art to which it appertains to make and use the same.

Our invention has for its object to provide an improved center pivot hinge for swinging window sashes; and, to this end, it consists of the novel devices and combinations of devices hereinafter described and defined in the claims.

In the accompanying drawings, which illustrate the invention, like characters indicate like parts throughout the several views.

Referring to the drawings, Figure 1 is a view of a window sash and frame, in vertical section, taken on the line $x^1 x^1$ of Fig. 2, said sash being supported from said frame by a pair of the improved hinges, for horizontal swinging movement, said window sash being open; Fig. 2 is a horizontal section, taken on the line $x^2 x^2$ of Fig. 1, with the window closed; Fig. 3 is a face view of the frame plate shown in Fig. 1, some parts of the window frame being broken away; Fig. 4 is a face view of the sash plate shown in Fig. 1, some parts of the sash being broken away; Fig. 5 is a face view of the frame plate shown in Fig. 1, removed from the window frame and also showing, in section, and broken lines, the co-operating sash plate in its two extreme positions; Fig. 6 is a detail view, in section, taken on the irregular line $x^6 x^6$ of Fig. 3; Fig. 7 is a detail view, in section, taken on the line $x^7 x^7$ of Fig. 4; and Fig. 8 is a detail view, in section, taken on the line $x^8 x^8$ of Fig. 2.

The numeral 1 indicates a window frame designed for a sash mounted on center pivots for horizontal swinging movement, and provided with the customary inner and

outer stops 2 and 3, respectively. To permit this swinging movement of the sash 4, it is necessary to terminate the stops 2 and 3 short of the pivotal supports for said sash, leaving an open space around said supports, between the sash and frame, through which the wind, dust, snow and rain may drive. Among various other improvements, our improved hinge is designed to completely close such openings, while at the same time permitting the sash to be readily removed from the frame, without the use of any tool whatsoever or without removing any of the parts of the hinge from either the sash or frame.

Each pair of the improved pivot hinges 70 comprises a frame plate 5 and a co-operating sash plate 6. Both plates 5 and 6 are set into the window frame and sash, respectively, so as to lie flush therewith, and are secured in position by wood screws, the heads of which are countersunk in said plates. It is, of course, understood that in case the frame and sash are constructed from metal the plates 5 and 6 may be riveted, or otherwise permanently secured, there-to. A pocket 7 extends obliquely into the frame plate 5 and has a semicircular bottom, at the axis of which is a trunnion seat 8, having an oblique entrance passage 9. The upper edge of the pocket 7 extends tangentially to the bottom thereof and parallel to the entrance passage 9, affording a stop surface 10. The junction of the bottom of the pocket 7 with the inner edge of the frame plate 5 affords a lower stop 11.

Integrally formed with the face of the sash plate 6 is a semicircular lug 12, having a V-shaped projection 13. This lug 12 is axially aligned with the pocket 7, of a diameter slightly less than that of said pocket, and is seated therein with its projection 13 extending upward between the stops 10 and 11. Integrally formed with the lug 12, and axially aligned therewith, is a trunnion 14, arranged to enter the seat 8, through the entrance passage 9, and detachably and removably seated therein. The lug 12 is of a thickness to permit the plates 5 and 6 to work close together, and, by reference to Fig. 1, it will be noted that the diameter 105 of this lug is sufficient to completely close the passageway between the stops 2 and 3. The engagement of the lug projection 13 with the stop 11 limits the opening movement of the sash 4. When the sash is closed 110

the projection 13 engages the stop 10 and, in this position of the lug 12, completely fills the pocket 7.

To hold the sash 4 closed and in different open positions, is provided a spring-held latch and a coöperating lock segment 15, integrally formed with the left hand frame plate 5, as viewed from the inside of the building. By reference to Figs. 3 and 5, it will be noted that the entrance passage 9 extends completely through the lock segment 15. At the junction of the lock segment 15 with the plate 5 is formed a lock notch 16, and the periphery thereof is formed with ratchet-like projections, which afford stop shoulders 17. The latch, as shown, is in the form of an intermediately pivoted bar 18 mounted in a casing 19, secured by screws or otherwise to the sash 4. This latch bar 18 extends through aligned openings in the casing 19 and is held in an operative position by the spring 20. The outer end of the latch bar 18 is arranged to ride over the periphery of the lock segment 15 and when it enters the lock notch 16 secures the sash 4 in a closed position. When either one of the stop shoulders 17 is engaged by the latch bar 18 the sash 4 is held open in a predetermined set position. The hanging of the sash 4 from the frame 1 is such that the same will tend to close under the action of gravity. In the inner end of the latch bar 18 is formed an eye to which is attached a latch-releasing cord 21, which is extended through a guide passage 22 in the casing 19 and through an eye 23, secured to the lower end of the adjacent side rail of the sash 4. Obviously, by pulling on this cord 21 the latch bar 18 is rocked on its pivot against the tension of the spring 20, out of engagement with the lock segment 15. The window frame 1 is recessed at 24, which recess is concentric with the lock segment 15 and affords a clearance passage for the latch bar 18.

When the sash 4 is open, as shown in Fig. 1, the same may be readily removed from the window frame by drawing outward thereon, to lift the trunnions 14 laterally out of the seats 8 through the entrance passages 9. While the drawings show one of the pivot hinges equipped with a lock segment, it is, of course, understood that the same may be dispensed with if a latch is not required.

What we claim is:

1. The combination with a window frame having an inner stop and an outer stop, spaced, the one above the other, and a window sash, of a pair of pivot hinges connecting said sash to said frame for swinging movement between the stops, each of said pivot hinges comprising a relatively fixed

plate and a relatively movable plate detachably pivoted thereto for edgewise separation, said plates having reversely off-set surfaces fitted one within the other, affording a substantially tight joint between the plates at their pivotal connection and extending above and below the inner ends of 70 the stops.

2. A pivot hinge comprising a relatively fixed plate and a relatively movable plate, said fixed plate having a pocket and an open seat, and said movable plate having 75 a trunnion equipment lug, seated in said pocket with its trunnions journaled in said seat, with freedom for separation therefrom by a lateral movement, said lug filling the pocket in one extreme position of the movable plate and projecting out of the pocket in the other extreme position of said movable plate.

3. A pivot hinge comprising a relatively fixed plate and a relatively movable plate, 85 said fixed plate having a pocket, with a semicircular bottom, an entrance passage terminating in a seat at the axis of said pocket, and said movable plate having a semicircular lug seated in said pocket, said 90 lug having a trunnion at its axis journaled in said seat with freedom for separation therefrom by a lateral movement through said entrance passage.

4. A pivot hinge comprising a relatively 95 fixed plate and a relatively movable plate, said fixed plate having an oblique pocket with a semicircular bottom, an oblique entrance passage terminating in a seat at the axis of said pocket, and said movable plate 100 having a semicircular lug with an extension, said lug being seated in said pocket, and having a trunnion at its axis journaled in said seat, the extension on said lug affording a stop to limit the oscillatory movement of said lug in said pocket.

5. A pivot hinge comprising a relatively fixed plate and a relatively movable plate, 110 said fixed plate having an oblique pocket with a semicircular bottom, an oblique entrance passage terminating in a seat at the axis of said pocket, and said movable plate having a semicircular lug with a V-shaped extension, said lug being seated in said 115 pocket, and having a trunnion at its axis journaled in said seat, the extension on said lug affording a stop to limit the oscillatory movement of said lug in said pocket.

In testimony whereof we affix our signatures in presence of two witnesses:

FRANK E. LARSCHEID.
FREDERICK W. CARLSON.
JOSEPH FIRNER.
